[57] CLAIM

The ornamental design for a cabinet for an aerosol spray dispenser, as shown and described.

DESCRIPTION

FIG. 1 is a top, front and right side perspective view of a cabinet for an aerosol spray dispenser showing my new design;

FIG. 2 is a front elevational view thereof, the undisclosed rear being plain and unornamented;

FIG. 3 is a top plan view thereof, the undisclosed bottom being plain and unornamented; and

FIG. 4 is a left side elevational view thereof, the right side being a mirror image.
